UNITED STATES PATENT OFFICE.

DUNCAN A. McCONNELL, OF ARLINGTON, NEW JERSEY, ASSIGNOR TO LOVELL-McCONNELL MANUFACTURING COMPANY, OF NEWARK, NEW JERSEY, A CORPORATION OF DELAWARE.

DIAPHRAGM-HORN.

1,228,226.

Specification of Letters Patent. Patented May 29, 1917.

Application filed January 7, 1914. Serial No. 810,801.

To all whom it may concern:

Be it known that I, DUNCAN A. McCONNELL, a citizen of the United States, and resident of Arlington, in the county of Hudson and State of New Jersey, have invented certain new and useful Improvements in Diaphragm-Horns, of which the following is a specification.

This invention relates to certain improvements in diaphragm horns and more particularly to that type in which the shaft is presented endwise to the diaphragm and carries the rotor for vibrating said diaphragm. One of the main objects of my present invention is to provide simple and efficient means for insuring the maintenance of the shaft in the desired adjusted position. I have illustrated my invention in a type of horn similar in many respects to that disclosed and claimed in my prior Patent No. 1,160,902, granted November 16th, 1915, on an application filed April 2, 1913. One feature of my present invention involves an improved and simplified form of motor frame adaptable 25 for use in a horn of the character disclosed in said prior application.

Reference is to be had to the accompanying drawings, in which similar reference characters indicate corresponding parts 30 throughout the several views.

Figure 1 is a central longitudinal section of a horn embodying my invention, said section being taken on the line 1—1 of Fig. 4, a part of the resonator being broken 35 away;

Fig. 2 is an inverted plan view, the motor casing and support being shown in section and the diaphragm and resonator being removed; and

40 Figs. 3 and 4 are sections on the lines 3—3 and 4—4, respectively, of Fig. 1.

I have illustrated my invention embodied in a horn employing a diaphragm 10 and a resonator or projector 11. The diaphragm 45 is illustrated as being held between the annular peripheral portions 12 and 13 of two diaphragm casing sections 14 and 15. Washers 16 of cork, fiber or other non-vibratory material, are preferably interposed between 50 the diaphragm and the faces of the clamping sections and suitable bolts or screws 17 hold the diaphragm casing sections, the

washers and the diaphragm in the proper relative positions. The front casing section 14 has a large central opening and presents 55 an annular flange 18 to which the resonator may be secured. The diaphragm at its center or in the vicinity thereof is provided with a suitable wear-piece 19 adapted to be engaged by the rotor to give the diaphragm 60 the desired vibrations. The construction and mounting of the diaphragm does not involve any portion of my invention and may be varied or changed without in any way departing from the spirit of my invention. 65

The armature shaft carries a rotor 21 in the form of a face cam or ratchet having projections, corrugations, irregularities or teeth adapted to successively engage with the wear-piece 19 or other thrust member. 70 The eccentricity of the armature shaft is substantially equal to the effective radius of the rotor, although it is evident that any other suitable and well-known means may be employed, for transmitting motion from the 75 operating face of the rotor to the center of the diaphragm. The particular arrangement of rotor and wear-piece illustrated constitute no portion of my invention, and therefore any other suitable means may be 80 employed in place of that shown for securing the vibration of the diaphragm upon the rotor of the armature shaft.

Preferably the rear diaphragm casing section 15 is in the form of a dished disk and 85 includes a transverse wall 22 spaced from the diaphragm and substantially parallel thereto and connected to the clamping portion 12 by an annular peripheral wall including a cylindrical portion 23 and an inclined or conical portion 24. The transverse wall 22 is spaced from the diaphragm a sufficient distance to permit the positioning of the rotor and wear-piece therebetween and permit the proper vibration of the dia- 95 phragm. This casing section has the transverse wall 22 provided with an opening 25 through which the wires or other conductors may freely extend.

This transverse wall 22 serves as a bearing 100 for one end of the armature shaft 20 and for supporting the opposite end I provide a substantially U-shaped frame member having side legs or bars 26 and 27 ex-

tending rearwardly from the wall 22 and a transverse portion 28 substantially parallel to the wall 22 but spaced therefrom and formed integral with the side bars 26 and 27.

5 The two parts may be secured together in any suitable manner as for instance by screws 29 extending through the wall 22 into the ends of the side bars 26 and 27.

The two side bars 26 and 27 serve to support the pole pieces of the motor and in fact may have inwardly projecting portions 30 integral therewith and constituting said pole pieces. The field coils 31 are preferably made up separately and after being provided with suitable casings to hold the separate wires of the coil together may be slipped on over the pole-pieces prior to the placing of the armature 32 there-between. Thus, the motor may be very easily assembled by first 15 slipping the coils over the pole-pieces, then inserting the armature thereon, and then securing the U-shaped frame member to the wall 22 by means of the screws 29. For holding the coils in position upon the pole-pieces and preventing their slipping inwardly or becoming accidentally displaced, so as to contact with the armature, I provide suitable spring clips 42 which may extend 20 across from one coil to the other and may be held from inward movement by engaging 25 with the pole-pieces.

The transverse member 28 of the motor frame is provided with a bridge 34 on its side away from the diaphragm, and the entire bridge is preferably integral with the motor frame. The two legs 33 and 35 of the bridge have alined openings substantially parallel to the transverse portion 28 of the motor frame, and within these openings 30 are brushes 36 which are adjustable and are held in place in any suitable manner, as for instance by screws extending inwardly from the outer surface of the transverse member of the bridge. The commutator is located 40 between the two legs on the bridge, and is thus readily accessible from each side. Two insulated wires 37 lead from the two coils to the outer ends of the two brushes and two insulated wires 38 lead from the coils 45 through the opening 25 to terminals on the inclined or conical wall 24. The terminals 50 may be of any suitable character. I have shown bolts extending through insulated bushings and having lock nuts at the outer 55 end for retaining the wires.

The end of the armature shaft preferably fits within a socket in the plug 48 screwed into the bridge 34, intermediate of the ends of the latter. This plug constitutes an adjustable thrust bearing, whereby the armature may be forced endwise a limited distance toward the diaphragm to insure the proper contact of the rotor with the diaphragm. At the opposite end of the armature and between the latter and the trans-

verse wall 22 I provide a leaf-spring 50 which normally tends to force the armature back into contact with the thrust bearing. The specific form of spring shown is a leaf spring normally bowed and perforated at 70 its center to receive the armature shaft. The ends of the spring engage with the transverse wall and the central portion engages with a washer or collar 55 on the armature shaft or on the armature. Upon assembling 75 the horn, the spring will normally push the armature back to such a position that the rotor will not properly contact with the wear-piece, but by means of the thrust bearing the armature and rotor are advanced 80 until the proper engagement is secured and the armature is held between the spring and the thrust bearing. This avoids the necessity of absolute accuracy in the forming or assembling of the parts and permits the taking up of wear on the rotor. The plug forming the thrust bearing may be held in place after adjusting, in any suitable manner, as for instance by a lock nut 41. It preferably has an annular external groove 90 communicating with an oil duct in the bridge as shown in Fig. 2. This groove communicates with the socket receiving the end of the armature shaft through a small passage as indicated in Fig. 1.

For lubricating the armature shaft at its opposite end I may provide a small duct 43, leading downwardly from the cylindrical wall 23 of the bearing of the armature shaft and upon the side toward the diaphragm, so as not to interfere with the armature or coils. For protecting the motor, I provide a thin casing 44 preferably of metal and preferably of cylindrical form. The casing is shown as being of cup-shape with the open 100 end slipping on to the cylindrical wall 23 and then held in place by suitable screws 45. The length of this cylindrical wall determines the endwise sliding movement of the casing and the casing is preferably 105 considerably smaller than the diaphragm, so that the inclined wall serves not only to limit the position of the casing 44, but connects the casing of small diameter to the diaphragm clamps of larger diameter. The 110 casing 44 also preferably covers the upper end of the oil duct 43 so as to protect the latter from dust and dirt.

It will be noted that by merely removing the two screws 45, the casing 44 may be 115 taken off and all of the parts of the motor will be exposed so that they may be adjusted, replaced or repaired without removing the motor from the horn. By extending the wires 38 from the field coils through the 120 opening 25 and mounting the terminals 46 on the inclined wall 24, it will be noted that the removal of the case 44 does not disturb the wiring connection to the motor and that the motor may be run and tested and its op- 125 130

eration noted with the casing removed. Any suitable means may be employed for supporting the horn, for instance a bracket 47 which may be secured to the diaphragm casting by two of the bolts, which hold the diaphragm clamping portions in position, as shown in Fig. 4.

Having thus described my invention, what I claim as new and desire to protect by Letters Patent, is:

1. In a horn or signaling device, the combination of an elastic diaphragm, a transverse member in the rear thereof, a high speed electric motor secured to said member and having its armature shaft journaled in said member and presented endwise to said diaphragm, a rotor carried by said shaft for effecting vibration of said diaphragm toward and from said rotor, an adjustable thrust bearing for limiting the axial rearward movement of said shaft and said rotor under the reaction of said diaphragm, and a bowed leaf spring disposed between the armature of said motor and the rear surface of said member for maintaining the armature shaft in engagement with said thrust bearing throughout the range of normal adjustment and operation of the device.
2. In a horn, a diaphragm, a diaphragm case having a substantially plain rear wall, an electric motor at the rear of said diaphragm case, the armature shaft of said electric motor extending through said plain rear wall and presented endwise to the diaphragm, an actuator mounted upon said armature shaft and disposed within the diaphragm case, an adjustable end thrust bearing for said armature shaft for moving the same toward the diaphragm, and a spring mounted on said shaft and having its end portions supported by said diaphragm case and its intermediate portion bowed toward said end thrust bearing to normally hold the armature shaft the maximum distance from the diaphragm.
3. In a horn, a diaphragm, a diaphragm case having a substantially plain rear wall, an electric motor at the rear of said diaphragm case, the armature shaft of said electric motor extending through said plain rear wall and presented endwise to the diaphragm, an actuator mounted upon said armature shaft and disposed within the diaphragm case, an adjustable end thrust bearing for said armature shaft for moving the same toward the diaphragm, and a spring mounted on said shaft and having its end portions supported by said diaphragm case and its intermediate portion bowed toward said end thrust bearing to normally hold the armature shaft the maximum distance from the diaphragm.
4. In a horn, a diaphragm, an electric motor at the rear of said diaphragm and having its armature shaft presented endwise to the diaphragm, a transverse wall between the armature of said motor and said diaphragm and through which said shaft extends, an actuator mounted upon said armature shaft and disposed between said wall and said diaphragm, an adjustable end thrust bearing for said armature shaft for moving the same toward the diaphragm and a spring mounted on said shaft and having its end portions supported by said wall and an intermediate portion bowed toward said end thrust bearing to normally hold the armature shaft the maximum distance from the diaphragm.

Signed at Newark in the county of Essex and State of New Jersey this 3rd day of January A. D. 1914.

DUNCAN A. McCONNELL.
